Primary Examiner—Jennifer Rivard*Assistant Examiner*—Melanie Levy(74) Attorney, Agent, or Firm—Ryan Kromholz & Manion, S.C.(57) CLAIM

The ornamental design for a foot spa bowl, as shown and described.

DESCRIPTION

FIG. 1 is a perspective view of our foot spa bowl;
FIG. 2 is another perspective view with the leg rests in an alternate position;
FIG. 3 is a front elevational view;
FIG. 4 is a rear elevational view;
FIG. 5 is a top plan view;
FIG. 6 is a right side elevational view; and,
FIG. 7 is a left side elevational view.
The broken line showing of a base and seat in FIGS. 1-7 is illustrative of environmental structure only and forms no part of the claimed design.
